(57) **CLAIM**

The ornamental design for needle holder for surgical application, as shown and described.

DESCRIPTION

FIG. 1 is a front perspective in a closed position view of a needle holder for surgical application according to the present invention.

FIG. 2 is a left side view in a closed position view of the needle holder for surgical application of FIG. 1.

FIG. 3 is a right side view in a closed position view of the needle holder for surgical application of FIG. 1.

FIG. 4 is a top view in a closed position view of the needle holder for surgical application of FIG. 1.

FIG. 5 is a bottom view in a closed position view of the needle holder for surgical application of FIG. 1.

FIG. 6 is a front view in a closed position view of the needle holder for surgical application of FIG. 1.

FIG. 7 is a rear view in a closed position view of the needle holder for surgical application of FIG. 1.

FIG. 8 is a front perspective view in an open position view of the needle holder for surgical application of FIG. 1.

FIG. 9 is a left side view in an open position view of the needle holder for surgical application of FIG. 1.

FIG. 10 is a right side view in an open position view of the needle holder for surgical application of FIG. 1.

FIG. 11 is a top view in an open position view of the needle holder for surgical application of FIG. 1.

FIG. 12 is a bottom view in an open position view of the needle holder for surgical application of FIG. 1.

FIG. 13 is a front view in an open position view of the needle holder for surgical application of FIG. 1.

FIG. 14 is a rear view in an open position view of the needle holder for surgical application of FIG. 1; and,

FIG. 15 is a smaller scale perspective of the needle holder for surgical application of FIG. 8 attached to an insert and handle for endoscopic suturing.

The dashed lines illustrate environment that does not form a part of the present invention, and no claim is made to the material illustrated with dashed lines.
